UNITED STATES PATENT OFFICE.

EDWARD DUDLEY LEWIS, OF ELMIRA, NEW YORK.

WATER-COOLED LIQUID-FUEL FEEDER FOR STOVES.

Application filed July 23, 1923. Serial No. 653,361.

To all whom it may concern:

Be it known that I, EDWARD DUDLEY LEWIS, a citizen of the United States, residing at Elmira, in the county of Chemung 5 and State of New York, have invented certain new and useful Improvements in Water-Cooled Liquid-Fuel Feeders for Stoves; and I do declare the following to be a full, clear, and exact description of the invention, such 10 as will enable others skilled in the art to which it appertains to make and use the same.

My invention relates to improvements in stoves which consume liquid fuel, such as 15 kerosene and gasoline, and the object of this invention is to provide in a simple manner, for keeping the liquid fuel sufficiently cool to overcome the dangers now prevalent with stoves of this nature.

20 With the foregoing in view the invention resides in the novel subject matter herein-after described and claimed, the description being supplemented by the accompanying drawing, in which a vertical sectional view 25 partly in elevation is shown, of an oil stove embodying my invention.

In the drawing, I have illustrated one simple form of my invention, in connection with an oil stove embodying the usual oil supply 30 tank 1 and horizontal oil feed pipe 2 for the burners 3. Instead of closing the free end of the pipe 2 by an ordinary screw cap in the usual manner, I pass a relatively small horizontal water pipe 4 in the horizontal portion 35 of the pipe 2, through said open end and close the latter by a suitable stuffing box 5 which also serves to secure the pipe 4 in place. The inner end of this pipe 4 is closed by a suitable plug or the like 6, while its 40 outer end is turned upwardly as indicated

at 7 and communicates with a suitable water supply tank 8. This tank is preferably disposed at the end of the stove opposite the fuel tank 1.

By keeping a quantity of water in the 45 tank 8, the pipe 4 will of course be filled, and the prevalence of the water in this pipe will prevent overheating of the oil in the feed pipe 2, and consequently the most serious 50 danger common to stoves of the character mentioned is overcome.

Within the scope of the invention as 55 claimed, numerous changes may be made and it will be obvious that my invention may be used in connection with any type of liquid fuel stove.

I claim: —

In an oil stove, a plurality of burners having depending fuel intakes, a comparatively large horizontally disposed fuel supply pipe 60 beneath and in communication with said intakes, the ends of said pipe extending through the opposite end-walls of the stove, one of said ends being upturned and the other end being open, a fuel container supported on the upturned portion of the pipe, a horizontal water pipe extending into said fuel pipe through the open end of the latter, said water pipe extending throughout the length of the horizontal portion of the fuel 70 pipe and having its outer end directed upwardly, a reserve water tank mounted on the upper end of said upwardly directed portion of the pipe and communicating therewith, and a stuffing-box closing said open end of the fuel pipe and serving to secure said water pipe in place.

In testimony whereof I have hereunto affixed my signature.

EDWARD DUDLEY LEWIS.
